POCKET MAGNIFIER CASE AND SUPPORT

Robert E. Gordenier, St. Paul, Minn., assignor to
 Brown & Bigelow, St. Paul, Minn., a corporation
 of Minnesota

Application September 28, 1950, Serial No. 187,250

1 Claim. (Cl. 88—39)

1 This invention relates to a pocket magnifier which folds into a compact package, the frame of which provides a support for the magnifier when it is in use.

A feature resides in a magnifier, which may be made of plastic or other suitable material such as glass, which is provided with shields for the surface of the magnifier to protect the same. The covers are adapted to fold over the surface of the magnifier to enclose the same and protect it against wear when not in use.

It is also a feature to provide a pocket magnifier wherein the magnifying element is formed of a single piece of plastic which is molded so that the magnifying portion thereof is centered in the plastic body. The four corners at the sides are formed with projecting lugs adapted to pivotally support the cover members and provided with bearing surfaces against which the ears of the covers engage to provide the rigid bearing means for the ends of the covers so that they may be rotated on the projecting lugs. The bearing surfaces and the lugs are formed integral with the body of the plastic magnifier plate.

I also provide recesses on the bearing portions adjacent the supporting lugs which receive an indented portion formed on the ears of the covers and which function to hold the covers either in closed position or open and project in a manner to form supporting members to hold the magnifier elevated from the article on which it is adapted to rest when being used as a magnifier.

In the drawings forming part of the specification:

Figure 1 illustrates a side view of the magnifier as it would appear in use.

Figure 2 is a plan view of Figure 1.

Figure 3 is an end view of Figure 1.

Figure 4 illustrates a side view of the magnifier when it is folded into a compact state.

Figure 5 is an end view of the magnifier as it would appear when folded.

Figure 6 is a perspective view of the plate body of the magnifier removed from the cover shields.

The magnifier A is formed with a plastic body 10 which may be molded from transparent plastic such as Lucite or a similar plastic which has a clear transparent nature. The body 10 may also be made of glass or any other suitable transparent material.

The body 10 of the magnifier A is in plate-like form, and centrally positioned within the same a magnifying portion 11 is formed by an arcuated surface which projects from either side of the plate body 10.

At each corner of the plate body 10, I form

2 integral with the plate, bearing portions 12 which have a flat surface 13 adapted to act as a bearing for supporting the cover shields 14.

The cover shields 14 are formed with side flanges 15 which are formed by bending portions along the edges of the shields 14 at right angles to the body of the shields, thus reinforcing the shields at their corners. The flanges 15 taper from the free end 16 to the ear portions 17 which are adapted to bear against the bearing portions 12 with spring tension. The spring tension to the ears 17 is provided by bending the ear portions 17 inwardly and thus causing a spring tension and friction against the bearing portions 12 to support the shields 14 in place.

The plastic lugs 18 project centrally from the bearing surfaces 12, and are adapted to engage in the hole 19 formed in the ear portions 17 to hold the cover shields to the plastic body 10 of the magnifier A.

Recesses 20 are formed in the bearing surfaces 12 which are adapted to engage the dents 21 formed in the ear portions 17 to hold the magnifier shields 14 projecting, as illustrated in Figure 1, so that the shields act as supporting members to hold the magnifier A elevated from the surface on which it is resting when in use.

Projecting ribs 22 are formed on the side edges of the body 10 of the magnifier A, and by means of the longitudinal dents 23 which engage over the projecting ribs 22, the cover shields 14 are held in closed position to extend over and cover and protect the magnifying surface 11 of the magnifier A when the magnifier is folded in compact state and carried in one's pocket. Thus, the cover plates 14 act to shield and protect the magnifying surface 11 from being scratched or marred when it is in folded position.

In this manner, I provide a simple inexpensive pocket magnifier which may be folded into a flat compact form and readily be opened with the covers 14 resting upon the surface which is magnified by viewing the same through the magnifier 11. The parallel disposed ribs 22 which project on the side surface of the flanges 15 readily engage over the ribs 22 to hold the cover members 14 in closed position.

The magnifier A is composed of three parts, namely, the plastic body 10 in which the magnifier surface 11 is formed centrally disposed therein and the two cover members 14, which are virtually identical, one of which folds against one side of the magnifier 11 while the other turns around the lug 18 to fold onto the other side as indicated by the arrows in Figure 1.

The inner edges 24 of the cover plates 14 form

a shoulder which rests against the body 10 when the covers 14 are moved into open position as illustrated in Figures 1 and 3.

The metal covers 14 with the side flanges 15 have a spring nature so that the ear portions 17 engage the bearing plate portions 12 under spring tension. The spring in the metal flanges 15 also engage the ribs 22 with spring tension sufficient to hold the covers 14 in closed position as illustrated in Figure 6, yet permitting the covers to 10 be rotated on the pivots 18 into the position illustrated in Figure 1.

The plate body 10 has formed on one end thereof the extended shoulder portion 25 adapted to be engaged by the inner edge 24 of the cover plate 14 whereby the cover plate 14 is maintained in the supporting position shown in Figures 1 and 2. The edge 24 of the remaining cover shield 14 engages the under flat surface of the plate body member as shown in dotted lines in Figure 2 and 20 also illustrated in Figure 1.

I claim:

In a magnifier having a combination support cover, a substantially fiat rectangular transparent body member having a magnifying element 25 formed thereon and extending therethrough to the opposed flat surfaces thereof, bearing members formed on each of the corners of said flat body member with the outer surfaces thereof at right angles thereto and flush with the outer 30 edges of said body member, stub shafts extending centrally from said bearing members at right angles to the edges of said body member, a pair of thin plate-like cover and support members each having parallelly disposed flanges formed 35

thereon and at right angles thereto, each of said plate-like members having a defined upper edge and in addition a defined lower edge adapted to rest upon a surface to support said magnifier spaced therefrom, ear portions extending from said flanges beyond said upper edges of said plate members, means for hingedly mounting said ear portions on said stub shafts and against the outer surfaces of said bearing members each of said upper edges of said cover plates forming a shoulder for engagement with the underside of said body member with said flanges extending in the same direction from said cover plates when said cover plates are rotated on said stub shafts to a position at right angles to said body member and in parallel opposed relation to place the same in open supporting position, said plates being adapted to cover both the opposed flat surfaces of said body member when said upper shoulder edges thereof are pivoted away from the under surface of said body member and said plates further moved onto the body member.
